United States Patent Office

Des. 207,909
Patented June 13, 1967

207,909

COMBINED BED, WARDROBE AND STUDY DESK UNIT

Simon W. Oppenhuizen and John O. Lockwood, both of
Grand Rapids, Mich., assignors to Uniline Corporation,
Holland, Mich.

Filed Sept. 30, 1965, Ser. No. 87,227

Term of patent 14 years

(Cl. D33—19)

FIG. 1 is a perspective view of the combined bed, wardrobe and study desk unit of the invention,

FIG. 2 is a top plan view of the unit,

FIG. 3 is a left-hand elevational view of the unit,

FIG. 4 is a fragmentary front elevational view of the right end of the unit including the bed, end portions of the wardrobe and study desk portions of the unit. The back of the unit is plain and unornamented.

We claim:

The ornamental design for a combined bed, wardrobe and study desk unit, as shown and described.
